UNITED STATES PATENT OFFICE

WILLIAM TAYLOR ALLAN, OF SHOTTS, SCOTLAND

METAL REINFORCEMENT FOR HIGHWAYS CONSTRUCTION

Application filed October 7, 1931, Serial No. 567,433, and in Great Britain November 20, 1930.

This invention relates to improvements in metal reenforcement for the construction of highways.

Metal reenforcement according to the invention is constituted by interlocking plates, preferably of cast iron, ribbed and apertured, each plate being formed with concavely or convexly curved edges or with concavely and convexly curved edges adapted to mate with the edges of adjacent plates.

The invention is illustrated in the accompanying drawing in which Figs. 1-3 are, respectively, a plan view, an end elevation, and a side elevation, of a plate. Fig. 4 is a vertical section drawn to a larger scale illustrative of the mating of adjacent plates.

Referring to the drawing each plate 1 is ribbed on one face, as at 2, and is provided with apertures, as 3. The plate is placed ribbed side uppermost immediately below the surface of the road and bedded evenly on the road foundation, its edges interlocking with the edges of adjacent plates 1¹, 1² as shown in Fig. 4. The convexly curved edge 4 of the plate 1 fits into the concavely curved edge 5² of plate 1² and the convexly curved edge 4' of the plate 1¹ fits into the concavely curved edge 5 of the plate 1. The interlocking joint prevents displacement of the plates and at the same time allows the relative inclination necessary for camber and gradients. The plates are held against lateral displacement by the curb of the roadway against which they are bedded, and also by the surfacing material of the roadway which penetrates the apertures 3 in the plates and makes contact with and adheres to the surface of the foundation exposed by the apertures 3. The ribbed structure of the plates strengthens the latter and at the same time provides a further means of adhesion for the surfacing material, this adhesion being assisted by the edges of the apertures 3. For curves and corners in the roadway, plates of a shape to meet requirements are used. The dimensions of the plates are varied to suit different conditions. The surfacing material may be tar macadam or some such material or a material which is plastic when laid.

I claim:

Metal reenforcement for roadways comprising interlocking foundation plates, said plates being ribbed on the upper side and apertured for receiving the surfacing material, and disposed ribbed-side-uppermost to engage the surfacing material of the roadway and to form pockets for receiving surfacing material keyed by the portions accommodated by the apertures, each plate being formed with curved edges adapted to mate with the edges of adjacent plates in all horizontal directions and allowing for the camber of the road.

In testimony whereof I have signed my name to this specification.

WILLIAM T. ALLAN.
